(57) **CLAIM**

The ornamental design for the modular information handling system bezel, as shown and described.

DESCRIPTION

FIG. 1 is a front right perspective view of modular information handling system bezel comprising the present invention; FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a front right perspective view of the modular information handling system bezel mounted in a rack of a similar information handling system bezel.

Broken lines shown in the drawings illustrate portions of the modular information handling system bezel, and form no part of the claimed design.
